CLAIM

The ornamental design for a quick release keychain with a whistle device, as shown and described.

DESCRIPTION

FIG. 1 is a perspective view of the device.

FIG. 2 is a view in side elevation taken from a first end of the device.

FIG. 3 is a view in side elevation taken from a second end of the device.

FIG. 4 is a view in side elevation taken from a first side of the device.

FIG. 5 is a view in side elevation taken from a second side of the device.

FIG. 6 is a plan view taken from the top of the device.

FIG. 7 is a plan view taken from the bottom of the device; and,

FIG. 8 is a perspective view of the device.

The broken lines in the drawings depict unclaimed portions of a quick release keychain with whistle device that form no part of the claimed design.

1 Claim, 6 Drawing Sheets
